(57) **CLAIM**

The ornamental design for an umbrella with solar panels, as shown and described.

DESCRIPTION

This application incorporates by reference U.S. patent application Ser. No. 29/461,658, filed Jul. 26, 2013.

FIG. 1 shows a perspective view of a first embodiment of a design for an umbrella with solar panels.

FIG. 2 shows a top view of FIG. 1; and,

FIG. 3 shows a side view of FIG. 1.

The broken lines in the figures depict portions of the umbrella with solar panels that form no part of the claimed design.
